Fred B. Bear, Lake St., Grayling, Mich.

Filed May 28, 1965, Ser. No. 85,491

Term of patent 14 years

(Cl. D30—1)

FIG. 1 is a side elevation of the handgrip adapter for archery bow showing my new design.

FIG. 2 is a perspective view of the adapter shown in FIG. 1 as it appears from one side.

FIG. 3 is a perspective view of the adapter shown in FIG. 2 taken from the opposite side.

FIG. 4 is a rear elevation of the adapter.

FIG. 5 is a front elevation thereof.

FIG. 6 is an enlarged side elevation of the adapter shown in FIG. 1 with the medial portion of the adapter shown in section as indicated on the line 6—6 of FIG. 5.

FIG. 7 is a cross-section of the adapter taken on the line 7—7 of FIG. 5.

The broken line portions of the archery bow are shown for purposes of illustration only.

I claim:

The ornamental design for a handgrip adapter for archery bow, as shown and described.
